(No Model.)

E. A. HANEY.
SAFETY GAS COCK.

No. 597,181.

Patented Jan. 11, 1898.

Thomas J. D. Hammond.

UNITED STATES PATENT OFFICE.

EUGENE A. HANEY, OF BOSTON, MASSACHUSETTS.

SAFETY GAS-COCK.

SPECIFICATION forming part of Letters Patent No. 597,181, dated January 11, 1898.

Application filed April 16, 1897. Serial No. 632,469. (No model.)

To all whom it may concern:

Be it known that I, EUGENE A. HANEY, of Boston, county of Suffolk, State of Massachusetts, have invented an Improvement in Safety Gas-Cocks, of which the following description, in connection with the accompanying drawings, is a specification, like letters on the drawings representing like parts.

This invention relates to safety gas-cocks, and has for its object the provision of a cock which will automatically lock itself when turned to closed position and effectually prevent accidental escape of gas after the flame has been thus extinguished, my improved cock presenting a construction which cannot be readily tampered with, is sure in operation, and at the same time easy to manipulate.

The various features of my invention will be fully illustrated and described in the accompanying drawings and specification, and set forth in the claims.

Figure 1 shows in side elevation a gas-fixture having a cock embodying my invention. Fig. 2 is a similar view of a modified form of construction. Fig. 3 is a rear elevation, partly in section, on the line xx of the construction shown in Fig. 2. Fig. 4 is a plan view of the casing and exposed portion of the operating parts, looking from bottom to top of Fig. 1. Fig. 5 is a plan view of the closure-plate shown in Fig. 2. Fig. 6 is a view in side elevation of another modification, Fig. 7 being a plan view thereof, looking from bottom to top.

In the preferred form of construction selected to illustrate my invention and shown in Figs. 1 and 4, A is a gas-fixture, of usual form and material, having a valve-seat a for the reception of a valve-plug B, of form suitable to enable the flow of gas to be regulated. Secured to this plug, and preferably formed integral therewith, is an extension b , of any suitable contour, carrying on a pivot b' a swinging lever or thumb-piece C, by which the extension and plug may be turned when the lever is in one position and which is adapted to be locked in another position to prevent turning of the plug.

To prevent tampering with the stop-cock, I have illustrated a casing D, which also serves as one form of support for means to lock the

operating-lever in desired position and is shown as a closed cylinder attached to the fixture A, in this instance its top d being apertured at d' to receive and engage a threaded shoulder a' on the fixture A, adjacent and surrounding the bottom of the valve-seat a . To prevent accidental displacement of this cylinder, I have shown additional attaching means intermediate the cylinder and casing, consisting in this instance of lugs a^2 , projecting downwardly from the fixture, the casing being secured to these lugs by screws d^2 , extending through the top d . The casing D, attached thus or in any suitable way to the fixture, is provided with means by which the lever C is to be locked, the means illustrated consisting of an apertured plate or closure E for the lower end of the casing and fixed to the latter in any suitable manner, as by pins d^3 .

The aperture e in the closure E is of suitable size to permit the passage therethrough of the swinging lever C and is enlarged centrally, in the preferred construction illustrated in Figs. 1 and 4, to allow the lever C to be turned about its longitudinal axis when in substantially vertical or dotted-line position, Fig. 1. The lever C is, however, subject to the action of suitable means, as a spring F, tending constantly to throw it out of its operative position, and when the plug B is in position (see Fig. 1) to prevent flow of gas, the lever C is, under the action of the spring F or such other suitable means as may be used, thrown into a notch e' , extending outwardly from the central aperture e , and is there firmly held from turning.

To hold the spring F up to its work, the spring is mounted on a rod f , extending through and carried by the lever C, the spring bearing at its ends, respectively, against the lever and an enlargement or head f' of the rod, which in turn rests against the inner wall of the casing. The other end also of the rod f may be provided with a head f^2 , if desired, and the lever C is provided, preferably, with a plate H to close the aperture e and prevent the entrance of dust or the insertion of tools or the like.

When the lever C has entered the notch e' , the plug B cannot be again turned until the

lever has been removed from the notch and brought to the dotted-line position, so that before turning on the gas the operator must draw the lever out of the notch, and an accidental turning on of the gas is thus rendered impossible.

To limit the range of the lever C to a quarter-turn in order that the gas may not be turned off and then on again by a continuous movement in the same direction, I have shown shoulders e², extending into the central aperture e. By these shoulders or their equivalent, carried by the casing, I am enabled to dispense with the arrangement with which gas-fixtures are at present provided, consisting of a shoulder on the under surface of the fixture proper adapted to engage a pin carried by the plug. Where my improved safety-cock is attached to existing fixtures, this arrangement may, if desired, be retained either alone or as an auxiliary stop, and I have in Fig. 2 so illustrated it, A' indicating an ordinary fixture having the usual shoulder a³ on the lower portion of the valve-seat to engage a pin b⁴ on the plug b³. In this figure the apertured top d⁴ of the casing D' is shown as not threaded, but as fitting snugly around the upper exposed portion of the plug b³ and against the shoulder a³, where it is held by suitable means, as screws d⁵, entering the blocks a⁴, secured to the fixture A' by soldering or otherwise. Within the casing D', which is similar in construction and function to the casing D, already described, is contained the extension b⁵ of the plug b³, also illustrated as similar to the plug extension b described, and to the extension b⁵ within the casing are connected, preferably by a pivot b⁶, two swinging levers c', similar to each other and to the lever C described, and under the influence of suitable means tending constantly to separate them and illustrated as a spring F', interposed between the levers and held in position by the rod f³, which is carried by the levers in suitable apertures. The locking means for these levers is shown as in the form of a closure-plate E', similar to the plate E, but having a plurality of notches e³, one for each of the levers C'. The shoulders e⁴ may be dispensed with, if desired, and the pin-and-shoulder stop a³ b⁴ relied upon, or vice versa.

By having a plurality of levers C', I relieve the fixture of the strain usually attending the use of a single lever and opposing spring, and this form of construction is particularly applicable to chandeliers, where such a strain is most undesirable.

In Figs. 6 and 7 I have shown the operating-lever C^X and the locking-plate E^X as constructed and arranged to permit the lever to be locked by the action of gravity, an auxiliary spring F^X, seated in a recess c of the lever, being used or not, as desired.

Normally the lever C^X depends vertically

within the notch e⁵, which in this form of construction is located directly under the pivot b⁸ at the center of the closure-plate E^X, a sector of which, amounting to about a quadrant, is cut away, as indicated at e⁶, to allow the lever C^X to be swung out and around to turn on the gas.

In Fig. 6 I have shown the operating-lever as pivoted to a winged thumb-plate b^X of the pattern ordinarily found on gas-fixtures existing at the present day, no extensive alteration thereof being necessary to prepare the same for attachment, as will be readily understood.

Preferably all the various parts of my improved safety-cock are formed of metal, but any suitable material may be used; nor do I restrict myself to the exact construction illustrated, since, so far as I am aware, I am the first to provide a safety-cock in which the plug-operating lever is itself movable for locking purposes.

Having described my invention, what I claim, and desire to secure by Letters Patent, is—

1. The combination with a gas-cock and its swinging operating-lever, of a locking-plate having a locking-notch to receive said lever, and means to support said plate in the path of the latter, substantially as described. 95

2. The combination with a gas fixture or conduit and a gas-cock therein, of a swinging operating-lever for and depending below said cock in continuation thereof, and adapted to swing into position to lock said cock, and means supported from and beneath said conduit, in the path of said lever, and adapted to coöperate with the latter to lock said cock at times, substantially as described. 95

3. The combination with a gas-cock, of a plurality of swinging levers connected thereto and normally held in separated position to lock the cock, said levers being adapted to be drawn together and when so drawn to serve as actuating means to be manually operated to turn the cock, substantially as described. 105

4. The combination with a gas-cock having a swinging inferiorly-dependant operating-lever, of means coöoperating with said lever to lock the cock, said means being supported beneath said cock, substantially as described. 115

5. The combination with a gas-cock having a swinging operating-lever, of means coöperating with said lever to lock the cock, a support for said locking means, and a casing therefor substantially as described. 120

6. The combination with a gas-cock having a swinging operating-lever, of means coöperating with said lever to lock the cock, and a casing surrounding the joint between said cock and lever and serving as a support for said locking means, substantially as described. 125

7. The combination with a gas-cock and its operating-lever, of a casing partially inclos- 130

ing said cock and lever at the region of their union, and a closure for said casing, said closure being apertured to permit the projection of the lever therethrough, and a recess opening from said aperture to receive and hold the lever in locked position, substantially as described.

In testimony whereof I have signed my name to this specification in the presence of two subscribing witnesses.
